Atlys.

UNITED STATES PATENT OFFICE.

FRANK W. MERRICK, OF DORCHESTER, MASSACHUSETTS, ASSIGNOR TO AMERICAN STAY COMPANY, OF EAST BOSTON, MASSACHUSETTS, A CORPORATION OF MASSACHUSETTS.

FASTENING-DRIVING MEANS FOR WELTS.

Application filed April 27, 1926. Serial No. 104,936.

My invention relates to a tool for driving fastenings, as for example tacks, for securing welts with spreadable portions, and will be best understood from the following description when read in the light of the accompanying drawing of one example of the invention, while the scope of the invention will be more particularly pointed out in the appended claims.

10 In the drawing:—

Fig. 1 is an elevation of the tool constructed according to my invention;

Fig. 2 is an elevation at right angles to Fig. 1;

15 Fig. 3 is a section on the line 3—3 of Fig. 2;

Fig. 4 is a fragmentary view corresponding to a section on the line 4—4 of Fig. 1, illustrating the tool applied to a welt for 20 the purpose of setting a tack; and

Fig. 5 is a view corresponding to Fig. 4 with the parts in a different position.

Referring to the drawing a support is provided in the form of a tubular body 1 25 in the bore 3 of which is reciprocably mounted a plunger 5 of a fastening driving means. At its outer end the tool is provided with an operating means in the form of a head 7 for the plunger, a coil 30 spring 9 surrounding the plunger and abutting at opposite ends respectively with the head and the end 11 of the support being provided for automatically returning the plunger when the head is released after being pushed toward the support for driving 35 the fastening. Adjacent its end opposite the head 7 the plunger carries a transversely positioned pin 13 the opposite projecting ends of which slide in the oppositely disposed slots 15 in the walls of the support.

As illustrated, opposite sides of the support are flattened as indicated at 17, these flattened portions being recessed as indicated at 19 for providing grooves receiving 45 and guiding the flat spring members 21. For securing the springs to the support the present construction provides plates 23 which fit the grooves 19 and are placed over the springs, the plates being secured to the support by means of screws 25.

The spring members at their forward ends are shown as converging toward each other as indicated at 27, herein providing a

wedge-shaped portion for the tool for insertion between the spreadable parts of the 55 welt. Conveniently the forward end of the plunger carries the fastening engaging part 29, the end of the plunger at opposite sides being tapered as indicated at 31 to provide a narrow end portion 33 of sufficient width 60 for causing the spring members to be forced apart a distance sufficient to permit the fastening engaging part 29 to pass between them. Herein the ends of the springs are notched as is indicated at 35 to permit the 65 springs to be passed over the head of a tack or the like employed for securing the welt in position, this construction also providing means for aligning the tack driving means with the tack.

In Figs. 4 and 5 I have indicated a welt having the base 37 and the portions 39 sewed to the base by stitches indicated at 41, the position of the stitches and the resiliency of the portions 29 permitting the latter to be spread apart to allow the tack or other fastening means to be driven. As will be understood, normally the two portions 39 substantially abut at their adjacent edges. When the welt is to be applied the fastening means may be driven for a part of their length as indicated by the tack shown at 43 in Fig. 4. The tool is then applied as indicated in Fig. 4, the notches 35 at the end of the springs serving to permit the springs to pass the head of the tack and to center the head of the tack with the tack engaging part 29. Forcing the plunger 3 into the position shown by Fig. 5 will cause the tack to be driven and the springs to force the spreadable portions 39 apart sufficiently to permit entry of the tack driving part between them. After the tack is driven and the tool is removed the spreadable parts 39 will spring back until their adjacent 95 edges abut.

Although I have described for purposes of illustration one example of the invention it will be understood that I am not limited thereto, but that wide deviations may be 100 made therefrom without departing from the spirit of the invention.

Claims:

1. A tool for driving fastenings for securing welts with spreadable portions having, in combination, means for spreading

said portions of the welt comprising relatively movable welt-spreading-parts for respectively engaging said portions, and fastening driving means for driving a fastening through that portion of the welt which is between the portions thereof engaged by said welt-spreading-parts.

2. A tool for driving fastenings for securing welts with spreadable portions having, in combination, fastening driving means, and fastening and welt-engaging means for centering a partially driven fastening beneath said driving means and spreading said portions of the welt to permit 15 said driving means to pass between them.

3. A tool for driving fastenings for securing welts with spreadable portions having, in combination, fastening driving means, and means actuated by said driving 20 means for spreading said portions of the welt.

4. A tool for driving fastenings for securing welts with spreadable portions having, in combination, a body carrying means 25 for spreading said portions of the welt, said body also carrying fastening driving means, and a common operating member carried by said body for actuating both means.

5. A tool for driving fastenings for securing welts with spreadable portions having, in combination, automatically retracted fastening driving means and automatically retracted welt portion spreading means.

6. A tool for driving fastenings for securing welts with spreadable portions having, in combination, separable parts respectively for engagement with the portions of the welt, and means for separating said parts and simultaneously driving a fasten- 40 ing.

7. A tool for driving fastenings for securing welts with spreadable portions having, in combination, separable parts respectively for engagement with the portions of 45 the welt, one of said parts yieldingly urged toward the other, and means for separating said parts and simultaneously driving a fastening.

8. A tool for driving fastenings for securing welts with spreadable portions having, in combination, parts formed for engagement with said portions of the welt, fastening driving means, and means for reciprocating said driving means and causing 55 said parts alternately to move away from and toward each other.

9. A tool for driving fastenings for securing welts with spreadable portions having, in combination, swinging parts for insertion between said portions of the welt, fastening driving means, and means for reciprocating said driving means and causing said parts alternately to swing away 60 from and toward each other.

65 10. A tool for driving fastenings for se-

curing welts with spreadable portions having, in combination, separable parts forming a wedge-shaped portion for insertion between said portions of the welt, and fastening driving means operative to separate said parts when said means is actuated to drive a fastening.

11. A tool for driving fastenings for securing welts with spreadable portions having, in combination, separable parts for insertion between said portions of the welt, one of said parts yieldingly urged toward the other, and fastening driving means operative to separate said parts when said means is actuated to drive a fastening. 75

12. A tool for driving fastenings for securing welts with spreadable portions having, in combination, a pair of flat springs converging toward each other at their ends for insertion between said portions of the 85 welt, and fastening driving means operative to separate said springs when said means is actuated to drive a fastening.

13. A tool for driving fastenings for securing welts with spreadable portions having, in combination, separable parts respectively formed for engagement with said portions of the welt, and fastening driving means operative to separate said parts when said means is actuated to drive a fastening. 90

14. A tool for driving headed fastenings for securing welts with separable portions having, in combination, means including separable parts each for engagement with one of said portions of the welt, said parts being so formed as to clear the head of the fastening to be driven, and means for separating said parts and driving said fastening. 95

15. A tool for driving headed fastenings for securing welts with separable portions having, in combination, means including separable parts for insertion between said portions of the welt, said parts being so formed as to clear the head of the fastening 100 to be driven, and means for separating said parts and driving said fastening. 11

16. A tool for driving headed fastenings for securing welts with separable portions having, in combination, a pair of flat spring 11 members converging toward each other at one end for insertion between said portions of the welt and being so formed as to clear the head of the fastening to be driven, fastening driving means, and means for reciprocating said driving means and causing said spring members alternately to move 12 apart and toward each other.

17. A tool for driving fastenings for securing welts with spreadable portions having, in combination, fastening driving means, and means for centering beneath said driving means a fastening to be driven and for spreading said portions of the welt. 12

18. A tool for driving fastenings for se- 13

curing welts with spreadable portions having, in combination, fastening driving means, and means including separable parts each for engagement with one of said portions of the welt, said parts being formed for centering a fastening to be driven beneath said driving means.

19. A tool for driving fastenings for securing welts with spreadable portions having, in combination, fastening driving means, means actuated by said fastening driving means for spreading said portions of the welt, said means for spreading said portions of the welt having means for centering a fastening to be driven beneath said driving means.

20. A tool for setting tacks for securing welts with spreadable portions having, in combination, a support, a pair of spaced

spring leaf members of material width carried by said support and converging toward each other at one of their ends to permit them to be inserted between the spreadable portions of the welt, and a resiliently retracted tack setting member slidably carried by said support for reciprocation between said spring leaf members, said setting member having portions for engaging said leaf members for spreading them apart when said setting member is moved toward the tack to be set, and said spring leaf members having their converging ends notched to permit them to be passed over the head of said tack.

In testimony whereof, I have signed my **25** name to this specification.

FRANK W. MERRICK.
